UNITED STATES PATENT OFFICE.

SOLOMON TRUSTMAN, OF DETROIT, MICHIGAN, ASSIGNOR OF ONE-HALF TO AMOS EMSLEY, OF DETROIT, MICHIGAN.

DESIGN FOR A COMBINED PHONOGRAPH AND LAMP STAND.

61,216.

Specification for Design.

Patented July 11, 1922.

Application filed November 30, 1921. Serial No. 518,997. Term of patent 14 years.

To all whom it may concern:

Be it known that I, SOLOMON TRUSTMAN, a citizen of the United States, residing at Detroit, in the county of Wayne and State of Michigan, have invented a new, original, and ornamental Design for a Combined Phonograph and Lamp Stand, of which the following is a specification, reference being had to the accompanying drawing, forming part thereof.

The figure is a perspective view showing my new design.

I claim:

The ornamental design for a combined phonograph and Lamp Stand as shown.

In testimony whereof, I sign this specification in the presence of two witnesses.

SOLOMON TRUSTMAN.

Witnesses:

S. E. THOMAS,
IDA GOREN.
